PAPER CUTTING MACHINE

Ralph S. Tyler, Cleveland Heights, Ohio, assignor
to The Chandler and Price Company, Cleveland,
Ohio, a corporation of Ohio

Application January 15, 1932, Serial No. 586,714

3 Claims. (Cl. 164—59)

This invention relates to paper cutting machines, and particularly to an improvement in the back gauges of such machines.

It is a primary object of the invention to provide a back gauge for a paper cutting machine which may be adjusted or swung in a vertical plane to bring the face of the gauge into a plane parallel with the knife of the machine, to provide means for effecting such adjustment in an easy and expeditious manner, and to provide, in connection with such adjustment means, means for facilitating the movement of the gauge in a direction longitudinally of the table of the machine. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a fragmentary side elevation of a paper cutting machine;

Fig. 2 is a plan view of the back gauge of the machine;

Fig. 3 is a transverse cross-sectional view through the gauge, taken on a plane indicated by the line 3—3 of Fig. 2;

Fig. 4 is a longitudinal cross-sectional view through the gauge, taken on a plane indicated by the line 4—4 of Fig. 2.

35 A paper cutting machine of a type now commonly used for cutting stacks of paper, cards, etc., includes a table 1 having secured to the sides thereof uprights 2 whose front faces form with the rear faces of guideway bars 3, slide-ways for the knife bar 4, which carries the knife 5. Side guides 5a may be secured to the table adjacent the front portion thereof.

The back gauge includes a central section 6 and the side sections 7 and 8. Bolts 9 extend 45 through apertures in the sides of the central section 6 and through slots 10 in one side of the side sections 7 and 8. With this arrangement, a relative longitudinal movement of the side sections with respect to the central section of the gauge is permitted, when it is desired to offset the front face of one or both side sections with respect to the front face of the central section, for reasons well understood by those skilled in the use of these machines. The 50 side sections may be secured in adjusted posi-

tion by means of nuts 11 secured to the ends of the bolts 9. The gauge sections are provided with forwardly extending gauge fingers 12, whose front edges constitute the front faces of the gauge sections.

5 The central section 6 of the back gauge is secured, as by means of a bolt 13, to a bar 14 which is adapted to be advanced or retracted along a slot 15 in the table by means of a cable (not shown).

10 Disposed within a recess 16 near the rear end of the central section of the gauge is a carriage 17 having bifurcated ends which serve as bearings for the support of freely rotatable ball-bearing rollers 18, which rest on the table 1.

15 In order to adjust the front face of the gauge to bring it into a plane parallel with the knife, the gauge may be tilted about the lower front edges of the fingers 12. For this purpose, I provide adjusting screws 19, lock nuts 20, and 20 retaining screws 21. The adjusting screws 19 are threadedly secured to the gauge and the lower ends of these screws rest on the carriage 17.

25 The retaining screws 21 extend through apertures in the gauge and are in threaded engagement with the carriage 17. When it is desired to tilt the gauge, it is only necessary to release the lock nuts 20 and turn the adjusting screws 19 in the desired direction to raise or lower the gauge, whereupon the lock nuts 20 may be again 30 tightened to preserve the adjustment. It will be understood that the retaining screws 21 are released during the adjustment and are tightened after the desired adjustment has been made.

35 The ball-bearing rollers 18 serve to carry the load of the back gauge and facilitate longitudinal movement of the gauge along the table, when such movement is desired.

40 Other modes of applying the principle of my invention may be employed instead of the one explained, change being made as regards the mechanism herein disclosed, provided the means stated by any of the following claims or the equivalent of such stated means be employed.

45 I therefore particularly point out and distinctly claim as my invention:

1. A back gauge for paper cutting machines and the like, comprising a gauge section, a carriage for supporting the rear end of said gauge 50 section tiltable about its front lower edge and provided with rollers for facilitating sliding of said gauge section, transversely spaced means for moving said gauge section with respect to said carriage to thereby tilt the gauge and means 55

for locking said gauge section to said carriage after said tilting movement.

2. A back gauge for paper cutting machines and the like, comprising a gauge section, a carriage for supporting the rear end of said section tilttable about its front lower edge having bifurcated ends, rollers supported in the bifurcated ends of said carriage, and means spaced transversely of the gauge for tilting the gauge section including screws extending through the gauge section and resting on said carriage and auxiliary screws for locking said gauge section to said carriage after the gauge section has been tilted to adjusted position.
- 10 15 3. A back gauge for paper cutting machines

and the like comprising a gauge section tilttable about its front lower edge, a housing adjacent the rear portion of said section, a carriage for supporting the rear end of said section, said carriage being disposed within said housing and comprising a bar having at each end thereof a pair of spaced downwardly extending ears, a shaft journalled in each pair of ears, and a roller mounted on each shaft and adapted to rest on a table or like support, and means for tilting the gauge section including screws adjacent the ends of and extending through the top wall of said housing and bearing against said carriage.
